[57] CLAIM

The ornamental design for a combined bracelet and rings, as shown and described.

DESCRIPTION

FIG. 1 is a perspective view of a combined bracelet and rings showing my new design therefor. The broken line drawing representing a hand is for purposes of illustration only and forms no part of my design. The broken line drawing depicting the word "Alan" is also for purposes of illustration and forms no part of my design.

FIG. 2 is a front elevational view;

FIG. 3 is a rear elevational view;

FIG. 4 is a top plan view;

FIG. 5 is a bottom plan view;

FIG. 6 is a left side elevational view; and,

FIG. 7 is a right side elevational view.

FIG. 1

FIG. 4**FIG. 2****FIG. 3**FIG. 5

FIG. 6

FIG. 7
